UNITED STATES PATENT OFFICE.

DANIEL A. KILMER, OF HOWE'S CAVE, NEW YORK.

BALE-TIE.

SPECIFICATION forming part of Letters Patent No. 228,648, dated June 8, 1880.

Application filed April 5, 1880. (No model.)

To all whom it may concern:

Be it known that I, DANIEL A. KILMER, of Howe's Cave, in the county of Schoharie and State of New York, have invented certain new and useful Improvements in Bale-Ties; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a perspective view of my bale-tie. Figs. 2 and 3 represent the ends of the tie detached.

15 The object of my invention is to produce a cheap, simple, and effective bale-tie, which will be more readily connected than the forms of bale-ties which approximate the nearest to the present device—such, for instance, as a 20 cross-bar rectangular in form pivoted in a loop provided upon one end of a band and combined with an outwardly-turned loop upon the other end of said band, such rectangular bar being expressly disclaimed by me.

25 The essential feature of the invention consists in a diamond-shaped plate swiveled upon the end of a twisted wire and adapted to be passed through an eye of the other end of the wire, and then, after being drawn taut, the 30 plate will lie crosswise of the eye, thus locking the tie.

In the drawings, A designates the twisted part of the wire, to which the diamond-shaped plate B is swiveled. C designates a twisted 35 end of the wire, which forms an eye, D.

In tying the bale the wire is drawn tightly around it and the swiveled diamond-shaped plate passed through the eye. By releasing the swiveled plate after it has been passed through 40 the eye its inclined sides will inevitably strike against the wire which forms the eye, thus turning the plate upon its pivot and causing it to lie crosswise upon the eye. In this posi-

tion it will be impossible to draw the diamond-shaped plate through the eye. The formation 45 of the plate will insure its turning and lying crosswise of the eye, since its slanting sides will invariably strike against the wire which forms the eye.

In baling, the eye and catch have in ordinary cases to be brought together at certain angles; otherwise it will be difficult to connect the two. In my form of tie the diamond-shaped plate may be slipped through the eye either from the side nearest to the bale, or 55 from what is usually termed the "outside"—that is to say, the side of the eye farthest from the bale.

The slightest penetration of the diamond-shaped plate within the eye will, as the parts 60 are brought together, guide the plate in its passage through the eye. This eye may be made to approximate to a perfect circle, and this form will readily guide the diamond plate in its passage.

Having thus described my invention, what I claim, and desire to secure by Letters Patent, is—

1. A bale-tie comprising a diamond-shaped swiveled plate and an eye adapted to admit 70 of the passage of the plate through it, the length of the plate being such as to admit of its lying crosswise upon the eye, in the manner set forth.

2. In a bale-tie, the swiveled diamond-shaped plate B, constituting a catch, in combination with the eye D, substantially as specified.

In testimony that I claim the above I have hereunto subscribed my name in the presence 80 of two witnesses.

DANIEL A. KILMER.
